UNITED STATES PATENT OFFICE.

HERMAN C. MAISE, OF SPRINGFIELD, MASSACHUSETTS, ASSIGNOR TO SPRINGFIELD BODY CORPORATION OF NEW YORK, OF SPRINGFIELD, MASSACHUSETTS, A CORPORATION OF NEW YORK.

CONVERTIBLE VEHICLE-BODY.

1,251,259.

Specification of Letters Patent. Patented Dec. 25, 1917.

Application filed July 7, 1916. Serial No. 107,908.

To all whom it may concern:

Be it known that I, HERMAN C. MAISE, a citizen of the United States, and a resident of Springfield, in the county of Hampden 5 and State of Massachusetts, have invented certain new and useful Improvements in Convertible Vehicle-Bodies, of which the following is a description.

My invention relates to convertible vehicle bodies and particularly to features of construction relating to the removable windows of such a body.

One object of my invention is to provide the vehicle door with means for retaining a 15 window in position when it is raised and for effectually concealing and protecting it when it is lowered.

Another object of my invention is to construct said-window retaining means so that 20 they will not detract from the external or internal appearance of the vehicle whether such means are in operative or in inoperative position.

Another object of my invention is to construct the window sashes in a particularly 25 durable and economical manner.

Other objects of my invention will appear more fully hereinafter.

Referring to the drawing, Figure 1 is a 30 side elevation of a vehicle equipped with a body made in accordance with my present invention.

Fig. 2 is a transverse sectional view taken through the vehicle door and showing the 35 window in elevated position.

Fig. 3 is a view similar to Fig. 2 but showing the window lowered.

Fig. 4 is a side elevation showing the window casing which is pivoted to the door with 40 the window retained therein.

Fig. 5 is a fragmentary transverse sectional view showing the manner in which the removable window sashes are retained in position.

Fig. 6 is a longitudinal sectional view 45 taken on the line 6-6 of Fig. 5, and

Figs. 7, 8, 9 and 10 are views showing the construction of the window casing and sash shown in Fig. 4 and are taken on lines 7-7,

8-8, 9-9 and 10-10 respectively of said 50 figure.

The vehicle shown in Fig. 1 is provided with a body having but a single door 11 on each side thereof. The window 12 shown partially lowered in this figure slides in the 55 casing 13 which casing is pivoted to the top of the door by means of the hinges 14. These hinges may be of any desired type but are preferably provided with some means such as indicated herein at 14^a for retaining the 60 casing in substantially vertical position above the door, as indicated in Fig. 2, and in the folded position alongside the door as shown in Fig. 3. The hinge described in the patent to Hinsdale Smith, No. 1,170,569, 65 February 8, 1916, and the hinge of my co-pending application, Serial No. 116416 filed August 23, 1916 are suitable for this purpose.

The top 15 of the vehicle is preferably 70 rigid and permanent and is supported by the back 16 and windshield frame 17. The removable window 18 is adapted to be positioned between the windshield frame 17 and the casing 13 and the removable window 19 75 is adapted to be positioned between the casing 13 and the back 16. When the windows 18 and 19 are removed and the window 12 and the casing 13 are lowered the sides of the vehicle are unobstructed from the back 80 16 to the windshield frame 17.

The casing 13 is preferably provided on the interior thereof with channeled guides or grooves 21 of such width as to embrace rather tightly the tongues 22 secured to the 85 window sash. As a result of this construction, when the window is elevated it is held firmly in position without danger of its vibrating, or rattling. When the window is lowered it is received in the pocket 20 of the 90 door 11.

It will be seen from an inspection of Figs. 2 and 3 that due to the configuration and disposition of the door 11 the pocket 20 is necessarily so arranged that the window 95 when disposed therein lies at an inclination to the casing 13 when that casing is in its elevated position, illustrated in Fig. 2. Be-

cause of this fact it is necessary to make provision whereby the window, when being lowered in the guides 21 of the casing may be swung into the necessary inclined position. I have therefore cut away one of the flanges of each of the channeled guides 21 near the bottom thereof as indicated at 23 in Figs. 4 and 8. This permits the window 12 to swing inwardly after it has been lowered 10 a certain amount and thus allows it to assume the inclined position required.

I have shown the pocket 20 provided with guide strips 24 which guide the lower portion of the window when the window is being lowered into the pocket. These guide strips are substantially straight near the top and in substantial alignment with the casing 18 when the latter is elevated. The initial lowering of the window 12 is therefore such 20 that the tongues 22 may be retained within the grooves 20. At a lower point, however, the guide strips 24 are curved as indicated at 25 and converge toward the interior edge 26 of the pocket 20 whereby the final lowering 25 of the window results in its being given the inclination shown in Fig. 3. As above indicated, this latter movement of the window is made possible by the cutting away of the channeled guides 21 near the bottom 30 thereof. A spring member such as is shown at 26^a is preferably provided to prevent the window from rattling when in the pocket 20.

When the window 12 has been lowered into the pocket 20 as indicated in Fig. 3 the 35 window casing 18 may be swung down upon its hinges 14—14 along side of the door. In order that the appearance of the inside of the door may be neat whether the casing 18 is raised or lowered I preferably provide 40 thereon a panel such as indicated at 27. This panel is preferably of such size that it will just fit within the casing 18. As a result when the casing 18 is lowered as shown in Fig. 3 the panel and casing together 45 form a substantially flush surface.

Any suitable means may be provided for retaining the window in its elevated position such for example as the catch 27^a shown in Fig. 4. Also a strap such as is shown 50 at 27^b in Fig. 2, provided with suitable fastening devices may be employed for elevating the window and for retaining it in any desired intermediate position. This strap is preferably concealed by the panel 27, as 55 illustrated.

In carrying out my invention I have employed a novel construction of window sashes and casings. This construction is best shown in Figs. 4 and 7 to 10 inclusive, 60 wherein the casing 18 and window sash 123 are illustrated as being made entirely of metallic tubing. Thus the window casing 18 comprises the side pieces or uprights 131, 132 and the top piece 133. The side pieces 65 are indented on the interior to form grooves

21 for the reception of the tongue 22 as above described and are bent on the exterior to form flanges 28 which are adapted to overlap the adjacent removable windows when the body is closed. The top piece 133 70 is indented or channeled only on the interior thereof as indicated at 29 for the reception of the tongue secured to the top of the window sash.

The window sash comprises the two uprights 121 and 122 and the top and bottom 123 and 124 respectively. Each of these pieces is indented or channeled on the interior thereof as indicated at 30 for the reception and retention of the pane of glass. 80 The uprights 121 and 122 are also channeled or dovetailed as shown at 31 to receive and retain the tongues 22 above referred to. The top member 123 is dovetailed at 32 to receive and retain the tongue 32', which, 85 when the window is raised fits within the channel 29 of the casing and forms a tight joint therewith. The tongues 22 and 32' are preferably constructed of a core of rigid material such as wood or metal surrounded 90 by a layer of flexible material such as felt or other fabric or rubber. The dovetail 33 in the exterior of the bottom member 124 of the window sash receives and retains the tongue 34 of a strip of resilient material 95 which strip cooperates with the top of the door to form a weather tight joint.

From the above description it is apparent that the window casing and sashes, which are made entirely of metallic tubing, are 100 very strong and durable and at the same time attractive in appearance and inexpensive in manufacture.

The sashes of the windows 18 and 19 are also preferably constructed of metallic tubing in substantially the same manner as above described. Thus as indicated in Fig. 5 the top member 181 of the sash of window 18 is indented or grooved on the interior as shown at 36 to receive the window pane 110 and is dovetailed at the top as shown at 37 to receive the tongue of the weatherstrip 38. I preferably cut away the strip 38 at intervals in its length and insert at these points metal blocks 39 which are provided 115 with tongues 40 which also fit within the groove 37. The top 15 of the vehicle is preferably provided with some sort of a guide such as indicated at 42 for the reception of the weatherstrip 38. Adjacent to 120 this guide and in register with the blocks 40 I provide means such as the screws 43 which when the removable sashes have been positioned are screwed up so that their pointed ends 44 contact with the bevel surface 45 125 of the blocks 40 and thus retain the windows firmly in place.

To convert the body above described into a closed body it is necessary merely to swing the casing 18 into the position illustrated 130

in Fig. 2, slide the window 12 up in the casing, and slide the windows 18 and 19 into place. In reconverting it into an open body the window 12 is slid down into pocket 20, 5 the casing 13 is swung down into the position indicated in Fig. 3, and the windows 18 and 19 are slid out of their guides and stored in suitable pockets or receptacles located at some convenient place in the vehicle. 10

It has heretofore been proposed to hinge the window sashes themselves to the top of the door and to swing the entire window down alongside the door when not in use, 15 and to provide pivoted guards to protect the window when swung down. When the window sashes themselves are hinged to the door, it is necessary that the window be wholly open or wholly closed, it being impossible to open the window partially as 20 shown in Fig. 1 of the drawing.

I am aware that the use of a casing hinged to a door and having a window sash slidable therein is not broadly novel. Such 25 casings are generally as thick as the door itself in order that the window may be moved from its inclined position within the door pocket, to its vertical position above the door. The use of such a bulky casing makes 30 a neat appearance impossible especially when the casing is folded down, and also necessitates the employment of additional means for holding the window against lateral movement when elevated. With my 35 present construction, on the other hand, the casing is of only sufficient thickness to embrace the sides of the slidable window, and it thus not only holds the window firmly in place but also gives to the body an attractive appearance whether the casing is elevated or lowered. The employment of the 40 flush panel 27 materially adds to the appearance of the interior of the door when the casing is lowered.

45 I do not wish to limit myself to the particular disclosure or description herein since obviously many changes may be made without departing from the spirit of my invention.

50 What I claim is:

1. In a convertible vehicle body, a door, a slidable window, and a window casing secured to the upper portion of said door and provided with channeled guides adapted to 55 contact simultaneously with both sides of said window and normally prevent lateral movement thereof, said door being provided with a pocket adapted to receive the window and retain it in an inclined position with 60 respect to said casing, said guides being partially cut away near the bottom to permit the window to slide into and out of said pocket.

65 2. In a convertible vehicle body, a slid- 130

ed to the upper portion of said door to be swung into substantially vertical position thereabove, channeled guides upon said casing adapted to engage both sides of said window simultaneously and normally prevent lateral movement thereof, said door being provided with a pocket adapted to receive the window and retain it in an inclined position with respect to said casing, said guides being partially cut away near the bottom to permit the window to slide into and out of said pocket. 70

3. In a convertible vehicle body, a door, a slidable window, a window casing hinged to the upper portion of said door to be swung 80 into substantially vertical position thereabove, channeled guides upon said casing adapted to engage both sides of said window simultaneously and by which the window is normally held against lateral movement, 85 said door being provided with a pocket adapted to receive the window and having therein downwardly converging guides aligned with the casing guides for a part of their length so that the initial movement 90 of the window into the pocket is in substantial alinement with the casing, said first named guides being partially cut away near the bottom for a distance equal to the converging portion of the pocket guides to permit the window to be moved to an inclined position within the pocket. 95

4. In a convertible vehicle body, a vehicle door, a window casing pivoted to the upper portion of said door and adapted to be folded down alongside said door, and a panel secured to the side of the door and adapted to be inclosed by the casing when folded down, whereby the panel and casing together form a substantially flush surface. 100

5. A vehicle body provided with a guide for a removable window sash, a removable window sash constructed of metallic tubing, said tubing being indented on the exterior of one side to form a groove, and a strip of 110 resilient material provided with a tongue adapted to be inserted in said groove to retain the strip in position so that it will cooperate with said guide when the window sash is in place. 115

6. A vehicle body provided with a guide for a removable window sash, a removable window sash constructed of metallic tubing, said tubing being indented on the exterior of one side to form a groove, a strip of 120 resilient material provided with a tongue adapted to be inserted in said groove to retain the strip in position so that it will cooperate with said guide when the window is in place, said strip being cut away at intervals, metallic blocks also provided with tongues which are adapted to be inserted in said groove at said intervals to retain the blocks in position, and means mounted adjacent the guide for co-operation with said 125 130

metallic blocks to hold the window sash firmly in place.

7. In a convertible vehicle body a window casing constructed of metallic tubing, a window sash slidably mounted in said casing and constructed also of metallic tubing, the tubing of the sash being indented on the ex-

terior of certain sides for receiving and retaining guiding tongues, the tubing of the casing being indented on the interior of certain sides to form grooves for the reception of said tongues. 10

HERMAN C. MAISE.
